UNITED STATES PATENT OFFICE.

ALBERT J. THROM, OF GRAPEVILLE, PENNSYLVANIA.

SKIMMER LADLE.

Application filed December 13, 1924. Serial No. 755,719.

To all whom it may concern:

Be it known that ALBERT J. THROM, a citizen of the United States of America, residing at Grapeville, in the county of Westmoreland and State of Pennsylvania, has invented new and useful Improvements in Skimmer Ladles, of which the following is a specification.

The object of the invention is to provide a device adapted for cleaning dirt and foreign matter from the top of the contents of pots such as are used in glass works; and to provide such adjustments in connection with the device as will permit ready swinging or moving of the ladle with respect to the handle, so that it may be brought against the sides of the pot and at the same time may be swung in the handle to present the edge to the top of the contents of the pot without necessity for having to change the position of the handle or carrying means with respect to the hand.

With these objects in view, the invention consists in the construction and combination of parts, of which a preferred embodiment is illustrated in the accompanying drawings, wherein:

Figure 1 is a top plan view of the invention.

30 Figure 2 is a longitudinal sectional view taken on the same plane as Figure 3 but showing the tilted position of the ladle.

Figure 3 is a longitudinal sectional view on the line 3—3 of Figure 1.

35 Figure 4 is a top plan view showing the angular position of the ladle. Figure 5 is a transverse sectional view on the plane indicated by the line 5—5 of Figure 4.

The ladle 1 is preferably trough-shaped and is pivotally supported in the yoke 2, the depending end arm 3 of which connects with the end walls 4 of the ladle. At an intermediate point in the yoke, the handle 5 is connected and this handle is preferably of 45 tubular form, being pivotally connected with the yoke, as at 6, and being provided beyond the pivot point with the fork 7 between the fingers of which the arm 8 carried by the rear wall of the ladle engages when 50 the ladle is in the tilted position indicated in Figure 2.

Carried within the handle is the tilting means for the ladle and such tilting means comprises a rod 9 formed at one end of the finger hold 10 and at the other end with an eye 11 which projects laterally from the

handle on the under side thereof. The operating rod 9 is capable of longitudinal movement in the handle and during such movement, the eye traverses a slot 12 formed on the under side of the handle adjacent the yoke. A link 13 connects the eye 11 with an eye 14 on the rear wall of the ladle adjacent the arm 8.

Obviously, longitudinal movement imparted to the operating rod by means of the finger hold 10 enables the tilting of the ladle to bring the lower forward wall in a horizontal position where the free edge is disposed so that it may be presented to the top of the contents of a glass pot and thus gather up the scum or foreign substance on top of said contents as the ladle is moved or dragged toward the operator. After the scum has been gathered, the movement of 75 the operating rod in the opposite direction restores the ladle to its normal position and thus the foreign matter which has been gathered therein may be readily removed and deposited with the proper waste.

In working around glass pots, it is necessary that the ladle be disposed so that it may be presented to the side of the pot, and to provide means for disposing it so that this operation may be readily accomplished, a 85 second operating rod 15 is provided. This rod is also housed in the handle and formed with a lateral projection 16 and operatively connected with a pivot stud 17 on the yoke disposed eccentrically to the pivot pin or 90 point of the handle, the means of connection being an angular link 18. The lateral pin or projection 16 of the rod 15 traverses a slot 19 formed in the handle directly above the slot 12 and the operating rod 15 is provided with a finger hold 20 by which longitudinal movement may be readily imparted to it.

The purpose of the fork 7 is to preclude oscillation of the ladle when the latter is tilted for skimming the top of the contents of a pot, for then the arm 8 engages between the fingers of the fork and oscillation of the ladle on the handle is precluded. However, when the ladle is oscillated to an angular 100 position in the handle, it may be rocked to dispose the forward free edge in skimming position as when scraping the surface of the contents, together with the side wall of the pot. By providing for disposing the ladle 110 in an angular position with reference to the handle, the handle is then in such a position

that it may not interfere with the scraping of the side of the pot, as would be the case were provision not made for oscillating the ladle to the angular position.

5 The invention having been described, what is claimed as new and useful is:

1. A device for the purpose indicated comprising a ladle, an operating handle for the same, and operative connections between the handle and the ladle, whereby the latter may be rocked to dispose its free edge in skimming position with relation to the contents of a glass pot or the like.

2. A device for the purpose indicated comprising a ladle, an operating handle, means for rocking the ladle to vary the relation of its skimming edge with respect to the handle, and additional means for oscillating the ladle to assume a position of angularity 20 with respect to the handle.

25 3. A device for the purpose indicated comprising a ladle, a yoke supporting the same and with which the ladle is pivotally connected with the yoke, and ladle rocking means slidably mounted in the handle and operatively connected with the ladle to vary the position of the skimming edge of the same with respect to the handle.

30 4. A device for the purpose indicated comprising a ladle, a yoke supporting the same, a handle having a pivotal connection with the yoke, and operating means housed in the handle and operatively connected with the yoke for oscillating the latter and the ladle 35 to cause the latter to assume different angular positions with respect to the handle.

40 5. A device for the purpose indicated comprising a ladle, a yoke by which the ladle is supported and in which it is pivotally mounted, an operating handle pivotally connected with the yoke at an intermediate point, and independently operable means housed in the handle and respectively connected with the yoke and the ladle for rocking 45 the latter to vary the position of its skimming edge with respect to the handle and for oscillating it to assume different angular positions with respect to the handle.

48 6. A device for the purpose indicated com-

prising a ladle, a yoke by which the ladle is 50 supported and in which it is pivotally mounted, an operating handle pivotally connected with the yoke at an intermediate point, independently operable means housed in the handle and respectively connected with the yoke and the ladle for rocking the latter to vary the position of its skimming edge with respect to the handle and for 55 oscillating it to assume different angular positions with respect to the handle, and co-operating means carried respectively by the handle and the ladle to preclude oscillatory movement of the ladle in one of the skimming positions of the same.

7. A device for the purpose indicated comprising a ladle, a yoke with depending arms pivotally connected with the ladle at its ends, a tubular operating handle having a pivotal connection with the yoke at an intermediate point in the latter, and operating 70 rods slidably mounted in the handle and having link connections respectively with the ladle and the yoke, whereby rocking movement may be imparted to the ladle in the yoke, and the yoke and the ladle oscillated with respect to the handle.

8. A device for the purpose indicated comprising a ladle, a yoke with depending arms pivotally connected with the ladle at its ends, a tubular operating handle having a 80 pivotal connection with the yoke at an intermediate point in the latter, and operating rods slidably mounted in the handle and having link connections respectively with the ladle and the yoke, whereby rocking 85 movement may be imparted to the ladle in the yoke, and the yoke and the ladle oscillated with respect to the handle, the handle being provided with a fork beyond the pivotal connection with the yoke and the 90 ladle having an arm engaging between the fingers of said fork to preclude oscillatory movement in one of the skimming positions of the ladle.

In testimony whereof he affixes his signature.

ALBERT J. THROM.
